BOX

Robert A. Bonn, New York, N. Y.

Application October 12, 1934, Serial No. 748,057

5 Claims. (Cl. 206—1.5)

This invention relates to boxes or containers of the type which may be used for the safe-keeping of valuables or for containing articles, access to which is to be made difficult, and for other uses. The object of the invention is to provide a box having a locking or closing mechanism so arranged that it lends an air of mystery or magic to the box in that the box cannot be opened without knowledge of its locking mechanism. Or at least, that the opening and the closing of the box occurs in a manner to arouse the curiosity and so that the box besides being useful may also serve as an amusing novelty.

To this end the invention is embodied in the box having means therefor so arranged that the cover can be opened only when the box is held in one certain position and a certain locking mechanism operated in a certain manner not easily ascertainable. In the accompanying drawing

Fig. 1 is a top view of the box.

Fig. 2 is a sectional view on line 2—2 of Fig. 1.

Fig. 3 is a sectional view on line 3—3 of Fig. 2.

Fig. 4 is a view similar to Figure 2 but shows the box turned upside down.

Fig. 5 is an end view of the box.

Fig. 6 shows a modification.

Fig. 7 is a detail view of parts of Figure 6.

The box consists of a bottom 10, two sides 11 and 12, and two ends 13 and 14. The top is open and is closed by a cover 15. The cover is hinged or pivoted to the box by a pin 16 which passes through the top and into a flange 17 at one end of the box. The flange 17 extends from side to side of the box and forms a sort of shelf therein. The cover is therefore mounted to be swung horizontally on the box to open it.

Normally such movement is made impossible because of a small stud 18 which is seated by gravity in a socket 19 in the flange 17 and which projects into another socket 20 in the cover. Thus the cover cannot be moved so long as the stud 18 engages the cover.

At the other end of the box there is located a sliding bolt 21 in a guide 22. The bolt is connected by means of a suitable looped wire or otherwise to a nipple 23 which carries a knob 24 outside the box. The nipple 23 extends through a slot 25 in the end of the box. The slot 25 is hidden from view by the knob. The bolt 21 has a normal position as shown in Figure 2, that is, it does not engage the cover. However, when the box is turned upside down the

bolt 21 will fall by gravity into a socket 26 in the cover.

The operation is as follows: Figure 2 shows what may be called the normal position of the box resting upon its bottom and with the cover locked and immovable. The box is opened first by turning it upside down as shown in Figure 4. In this position the stud 18 has fallen by gravity from the socket 19 in the box into the socket 20 in the cover below the dividing line, so this stud no longer engages the box and forms no hindrance to the swinging movement of the cover. However, when the stud 18 becomes disengaged from the box, the bolt 21 falls by gravity into engagement with the cover and enters the socket 26 therein. Consequently the cover, while being automatically unlocked at 19 is now automatically locked at 26 and cannot be opened until one takes hold of the knob 24 and lifts the sliding bolt up out of the cover socket 26. Then the box is opened by swinging the cover to either side on the pin 16.

It will be seen therefore, that a person not knowing the mechanism of the box will be mystified in trying to open it and may never succeed in opening it because the box must be held in the exact upside-down position before the locking means may be operated to permit movement of the cover. The knob is freely turnable in the nipple 23 and this also will mislead and confuse because one will imagine that rotating the knob has something to do with opening it. Even should a person discover the sliding movement of the knob in the slot 25 this will only help to still further mystify him because he will have no knowledge of the stud 18 and its functions.

For the purpose of increasing the mysterious or misleading features of the box, the cover and bottom are shaped alike as seen in Figure 3, the flattened portions 30 enabling the box to rest in a normal position like any other box. Although the top of the pin 16 may be seen from the top, it may lead one to think that it is a depressible bottom and thus also serves as a misleading feature.

Figures 6 and 7 illustrate a modification in which the box is provided with hooked members 31, 31 which project in over the cover to prevent forcible opening thereof by inserting a tool in the dividing line between cover and box. The cover will be shaped as shown in Figure 6 to permit it to be swung open as shown in dotted lines. A second dummy knob 35 is attached to the box in Figure 6 to still further mislead. It

may of course also be attached to the box in Figure 1.

The box may be made of any suitable material and in any size. It may be ornamented alike on the cover and bottom both for the sake of appearance and for misleading purposes. It will be noted that the box is locked irrespective of whether it has the cover or bottom uppermost and that tilting the box only serves to increase the difficulty of opening.

10 I claim:—

1. A box having an open top, a cover to close said box, means for swingably mounting the cover on the box to open the same, gravity operated means at each end of the box for normally preventing opening movement of the cover in either normal or inverted position, the gravity operating means at one end of the boxes being always invisible and means for manually operating the 15 other of said gravity operated means to open the box.

2. A box having an open top, a cover to close said box mounted thereon, invisible gravity operated means preventing the cover from being opened when the box rests on its bottom, other gravity operated means preventing the cover from being opened when the box is turned upside down and mechanism for rendering said last 20 named gravity operated means inactive to permit opening of the box in its upside down position.

3. A box having an open top, a cover to close the box mounted thereon, a gravity operated stud in said box in engagement with the cover to prevent opening thereof in all positions except when the box is turned upside down, a gravity operated bolt in the box adapted to engage the cover to prevent opening thereof when the box is turned upside down and means operable from outside the box for disengaging said sliding bolt from the cover to permit opening the box.

4. A box having an open top, a cover to close the box mounted thereon, gravity operated means in the box engaging the cover to prevent opening when the box is held in a given position, other gravity operated means in the box engaging 15 the cover to prevent opening when the box is held in another certain position, said first mentioned means then being automatically disengaged from the cover and mechanism for operating the said other means to permit opening 20 of the box.

5. A box, a cover therefor, means for mounting the cover on the box to permit opening thereof by a swinging movement of the cover, invisible gravity operated means in the box automatically 25 preventing opening thereof irrespective of the position in which the box is held and mechanism operable from outside the box for operating certain of said invisible gravity operated means to permit opening the box.

30 ROBERT A. BONN.
